LUBRICATING DEVICE

Filed April 2, 1928

Inventor :
John O. Lewis,
by Charles E. Yuller
His Attorney

UNITED STATES PATENT OFFICE

JOHN O. LEWIS, OF WESLEYVILLE, PENNSYLVANIA, ASSIGNOR TO GENERAL ELECTRIC COMPANY, A CORPORATION OF NEW YORK

LUBRICATING DEVICE

Application filed April 2, 1928. Serial No. 266,485.

My invention relates to oil reserve bearing lubricating devices of the type employing a storage reservoir in which oil is contained below atmospheric pressure above an outlet 5 opening formed in the lower portion thereof, and from which the flow of oil is regulated by arranging the outlet or a vent tube to control the admission of air to the upper portion of the reservoir.

10 In filling the reservoir in a device of this kind it is necessary to increase the pressure therein to atmospheric, or above, before oil will flow into the same. The increase in pressure in the reservoir permits an unrestricted 15 flow of oil therefrom, and heretofore in order to avoid flooding the bearing, a valve has been arranged in the reservoir outlet which is closed during the filling operation, or a porous obstruction has been placed in the outlet 20 to feed oil therefrom and to limit the flow of oil from the reservoir during the filling operation. A valve in the outlet is objectionable because attendants are likely to forget to open the same after the filling operation 25 so that the supply of oil to the bearing is cut off. The use of a porous obstruction in the reservoir outlet is unsatisfactory because it often clogs so as not to properly feed oil to the bearing or becomes displaced so that the 30 bearing is flooded. Moreover, if oil is forced into the reservoir the porous obstruction is very likely to either be displaced or permit such a rapid flow of oil therethrough from the reservoir that the bearing is flooded. 35 Furthermore, these devices have not generally provided any arrangement for indicating when the reservoir was filled, so that the attendant often continued pouring oil into the reservoir after it was full and flooded the bearing. This has been particularly troublesome 40 when the reservoir was filled by a pump or other pressure device.

The object of my invention is to provide a lubricating device of this type in which flooding of the bearing during filling of the reservoir is avoided and in which the oil overflow from the reservoir is arranged to give an indication that it is full. I prevent flooding of the bearing during the filling operation 45 by arranging an outlet in the reservoir and

providing means for supplying oil from the outlet to the bearing which is formed and arranged to provide for introducing a filling tube into the outlet to direct oil into the reservoir and to prevent the flow of oil therefrom through the outlet during the filling of the same. In order to provide an indication when the reservoir is filled, I arrange an overflow opening into the upper portion of the reservoir which discharges at a point in view 55 of an attendant filling the reservoir.

50 My invention will be more fully set forth in the following description referring to the accompanying drawing and the features of novelty which characterize my invention will 60 be pointed out with particularity in the claims annexed to and forming a part of this specification.

55 In the drawing, Fig. 1 is an end view partly broken away, of a motor bearing having 70 my improved lubricating device applied thereto; Fig. 2 is a sectional view on the line 2—2 of Fig. 1; Fig. 3 is a sectional view on the line 3—3 of Fig. 1; Fig. 4 is a slight modification of the lubricating device shown in 75 Fig. 1, and Figs. 5 and 6 are sectional views on the lines 5—5 and 6—6 respectively, of Fig. 4.

80 Referring to the drawing, the construction shown in Figs. 1 to 3 inclusive, is an end head 10 of a motor having a bearing 11 therein in which the motor shaft 12 is journaled. A pocket 13 is formed in the end head with an opening 14 in one side above the bottom thereof communicating with the bearing, and oil is fed to the bearing from a substantially 85 constant level at 15 below the opening 14 by an absorbent material 16, such as waste or the like, so as to make uniform the rate of feeding oil to the bearing. In order to exclude dust and dirt from the pocket 13 and afford 90 access thereto for repacking the absorbent material, a removable cover 17 is provided having a vent opening 18 therein so that air pressure in the pocket will not interfere with 95 feeding of the oil to the bearing. Oil is supplied to the pocket 13 at constant level from the outlet 19 of a storage reservoir 20 adapted to contain oil above the level 15, below atmospheric pressure, and the flow of oil from 100

the reservoir is regulated by controlling the admission of air thereto.

In accordance with my invention the means for supplying oil from the reservoir to the pocket 13 at constant level is formed and arranged to provide for introducing a filling tube into the reservoir outlet to direct oil into the reservoir and to prevent the flow of oil therefrom through the outlet during filling the reservoir. In the construction shown in Figs. 1 to 3, for example, this is done by arranging a receptacle 21 at the lower portion of the reservoir into which the outlet 19 discharges and forming an opening or extension 22 on the receptacle in alignment with the axis of the outlet. In this way a suitable filling tube 23, indicated in dotted lines in Fig. 1, can be placed in the extension 22 with the end thereof in the outlet so as to direct oil into the reservoir and prevent the flow of oil from the reservoir through the outlet during the filling operation. The extension 22 and the filling tube 23 are made in any convenient manner so as to permit an overflow of oil from the receptacle 21 when the tube 23 is in the extension, but for convenience in illustration I have for this reason shown the extension 22 of slightly larger diameter than the tube 23. Oil is supplied to the pocket 13 from the receptacle 21 by a passage 24 which also communicates by an opening 25 with a chamber 26 adjacent the pocket 13 which contains a body of oil to further insure uniform flow of oil to the bearing. The chamber 26 is vented through an opening 27 in the upper portion thereof which opens into the pocket 13 below the top of the absorbent material, but the latter is porous enough to allow the passage of air to the chamber from the vent opening in the pocket cover. The receptacle 21 is also vented through the extension 22 so that the oil level in the receptacle and the chamber 26 remains the same.

The oil level in the receptacle 21 and chamber 26 is maintained substantially constant at 15 below the opening 14 in the bearing by providing a vent tube 28 in the reservoir 20 which opens into the upper portion thereof and into the receptacle at the level 15. A nipple or short piece of pipe 29 is threaded into the end of the vent tube so that it can be replaced or adjusted to vary the height of the level 15 below the bearing opening 14, and a removable plug 30 is arranged in the bottom of the receptacle 21 to afford ready access to the nipple. As long as the level of oil in the receptacle 21 is at 15, the end of the vent tube 28 is sealed by the oil which prevents the admission of air to the reservoir so that oil is retained therein below atmospheric pressure. However, when the oil level in the receptacle 21 falls below the level 15, air is admitted to the reservoir through the vent tube 28 which increases the pressure

in the reservoir. Oil then flows from the outlet 19 into the receptacle until the oil level in the latter seals the ends of the vent tube and the pressure of the air in the reservoir above the oil therein is reduced sufficiently to support the head of oil in the reservoir above the outlet 19.

When it becomes necessary to fill the reservoir 20 the filling tube 23 is introduced into the outlet through the extension 22, as shown in dotted lines in Fig. 1, which prevents the flow of oil from the reservoir through the outlet. Moreover, if the filling tube delivers oil under high pressure, its being placed in the outlet 19 prevents oil being forced into the bearing 11 during filling the reservoir. As oil flows into the reservoir the oil level therein rises, increasing the pressure of the air above the oil level so that air is forced out of the reservoir through the vent tube and through the oil in the receptacle. After the reservoir is filled oil flows out of the vent tube 28 into the receptacle 21 and raises the oil level therein until oil flows out of the extension 22 along the filling tube 23, giving the attendant a positive indication when the reservoir is full.

The modification of my improved lubricating device shown in Figs. 4 to 6 inclusive, is also applied to the end head 10' of a motor having a bearing 11' therein in which the motor shaft 12' is journaled. A pocket 13' is formed in the end head adjacent the bearing 11' with an opening 14' therein above the bottom thereof communicating with the bearing and oil is fed to the bearing from a substantially constant level 15' below the opening 14' by an absorbent material 16' such as waste or the like. The pocket 13' is provided with a cover 17' having a vent opening 18' therein so that air pressure in the pocket will not interfere with feeding oil to the bearing. An oil reservoir 20' has an outlet 19' in the lower portion thereof which communicates directly with a receptacle 21' having an extension 22' in alignment with the outlet 19' so that a filling tube 23', shown in dotted lines in Fig. 4, can be introduced into the outlet for directing oil into the reservoir and for preventing the flow of oil through the outlet during filling the reservoir. The oil level is maintained substantially constant in the receptacle 21' by arranging a vent tube 28' with one end opening into the top of the reservoir and the other end opening into the receptacle 21'. In order to provide for adjustment of the oil level in the receptacle the end of the vent tube is formed with two threaded openings 29', one of which is closed by a plug 31', so that by changing the plug from one opening to the other, the level in the receptacle can be varied. The receptacle 21' communicates with the pocket 13' by an opening 32', which is clearly shown in Fig. 5, so that oil is fed from the constant

level 15' by the absorbent material 16' in the pocket.

The mode of operation of the foregoing described construction will be readily apparent from the detailed description of the operation of Figs. 1 to 3, as the former operates in substantially the same way as the latter.

Although my improved lubricating device has been shown as applied to the end head of a motor, it may readily be applied to bearings generally, so that I do not desire my invention to be limited to the particular construction shown and described, except as defined in the appended claims.

What I claim as new and desire to secure by Letters Patent of the United States is:

1. In combination with a bearing, a lubricating device comprising a storage reservoir adapted to contain oil below atmospheric pressure, said reservoir having an outlet in the lower portion thereof, and means for supplying oil to said bearing from said outlet formed and arranged to provide for introducing a filling tube into said outlet to direct oil into said reservoir and to prevent the flow of oil therefrom through said outlet during filling said reservoir.

2. In combination with a bearing, a lubricating device comprising a storage reservoir adapted to contain oil below atmospheric pressure, said reservoir having an outlet in the lower portion thereof, means for supplying oil to said bearing from said outlet formed and arranged to provide for introducing a filling tube into said outlet to direct oil into said reservoir and to prevent the flow of oil therefrom through said outlet during filling said reservoir, and means for conducting air from said reservoir during filling the same.

3. In combination with a bearing, a lubricating device comprising a storage reservoir adapted to contain oil below atmospheric pressure, said reservoir having an outlet in the lower portion thereof, means for supplying oil to said bearing from said outlet formed and arranged to provide for introducing a filling tube into said outlet to direct oil into said reservoir and to prevent the flow of oil therefrom through said outlet during filling said reservoir, and means including an oil sealed vent tube for conducting air from said reservoir during filling the same and for providing an overflow of oil from said reservoir to indicate when it is full of oil.

4. In combination with a bearing, a lubricating device comprising a storage reservoir having an outlet in the lower portion thereof and a vent passageway terminating at one end inside of the upper portion of said reservoir and at the other end outside of said reservoir, and means for supplying oil to said bearing from said outlet formed and arranged to provide for introducing a filling tube into said outlet to direct oil into said reservoir and to prevent the flow of oil therefrom through said

outlet during filling said reservoir, said oil supplying means being arranged to provide an oil seal for said vent passageway.

5. In combination with a bearing, a lubricating device comprising a storage reservoir having an outlet in the lower portion thereof and a vent passageway terminating at one end inside the upper portion of said reservoir and at the other end outside of said reservoir, and means for supplying oil to said bearing from said outlet having an extension in alignment with the outlet of said reservoir to provide for introducing a filling tube into said outlet to direct oil into said reservoir and to prevent the flow of oil therefrom through said outlet during filling said reservoir, said oil supplying means being arranged to provide an oil seal for said vent passage and to provide an overflow from said reservoir through said extension to indicate when said reservoir is full.

6. In combination with a bearing, a lubricating device comprising a storage reservoir adapted to contain oil below atmospheric pressure, said reservoir being arranged at one side of said bearing and having an outlet in the lower portion thereof, a pocket extending below the top of said reservoir on the other side of said bearing, absorbent material in said pocket for feeding oil therefrom to said bearing, and means for supplying oil from said outlet to said pocket and at a substantially constant level, said means being formed and arranged to provide for introducing a filling tube into said outlet to direct oil into said reservoir and to prevent the flow of oil therefrom through said outlet during filling said reservoir.

7. In combination with a bearing, a lubricating device comprising a storage reservoir adapted to contain oil below atmospheric pressure, said reservoir being arranged at one side of said bearing and having an outlet in the lower portion thereof, a pocket on the other side of said bearing extending below the top of said reservoir, absorbent material in said pocket for feeding oil therefrom to said bearing, and means including an oil sealed vent tube for supplying oil to said pocket at substantially constant level, said oil supplying means being formed and arranged to provide for introducing a filling tube into said outlet to direct oil into said reservoir and to prevent the flow of oil therefrom through said outlet during filling said reservoir.

8. In combination with a bearing, a lubricating device comprising a storage reservoir adapted to contain oil below atmospheric pressure, said reservoir being arranged at one side of said bearing and having an outlet formed in the lower portion thereof, a receptacle communicating with said outlet formed and arranged to provide for introducing a filling tube into said outlet to direct oil into

said reservoir and to prevent the flow of oil therefrom through said outlet during filling said reservoir, a pocket on the other side of said bearing communicating with said open receptacle and having an absorbent material 5 therein for feeding oil to said bearing, and means including an oil sealed vent tube having one end opening into the upper portion of said reservoir and the other end opening into said receptacle, for maintaining a substantially 10 constant oil level in said pocket and for providing an overflow from said reservoir to indicate when the same is full of oil.

9. In combination with a bearing, a lubricating device comprising a storage reservoir 15 adapted to contain oil below atmospheric pressure, said reservoir being arranged at one side of said bearing and having an outlet formed in the lower portion thereof, a receptacle 20 communicating with said outlet formed and arranged to provide for introducing a filling tube into said outlet to direct oil into said reservoir and to prevent the flow of oil therefrom through said outlet during filling said reservoir, said receptacle having a tubular 25 extension in axial alignment with said outlet for supporting a filling tube therein, a pocket communicating with said receptacle and having an absorbent material therein for feeding oil to said bearing, and means including 30 an oil sealed vent tube having one end opening into the upper portion of said reservoir and the other end opening into said receptacle for maintaining a substantially constant oil level adjacent said pocket and 35 for providing an overflow from said reservoir to indicate when the same is full of oil.

10. In combination with a bearing, a lubricating device comprising a storage reservoir 40 adapted to contain oil below atmospheric pressure, said reservoir having an outlet in the lower portion thereof, means for supplying oil from said outlet to said bearing including a receptacle extending below the top of said reservoir, an extension on said receptacle 45 formed and arranged to provide for introducing a filling tube into said outlet to direct oil into said reservoir and to prevent the flow of oil therefrom through said outlet during filling said reservoir, and means for maintaining a substantially constant oil level 50 in said receptacle comprising a vent tube communicating with the upper portion of said reservoir and said receptacle, said vent tube providing an overflow from said reservoir 55 through said receptacle and said extension to indicate when said reservoir is filled.

11. In combination with a bearing, a lubricating device comprising a storage reservoir 60 adapted to contain oil below atmospheric pressure, said reservoir having an outlet in the lower portion thereof, means for supplying oil from said outlet to said bearing including a receptacle extending below the top of 65 said reservoir, an extension on said receptacle

formed and arranged to provide for introducing a filling tube into said outlet to direct oil into said reservoir and to prevent the flow of oil therefrom through said outlet during filling said reservoir, said extension being 70 formed to allow oil to overflow from said receptacle between said extension and the filling tube when the filling tube is placed in said extension, and means for maintaining a substantially constant oil level in said receptacle comprising a vent tube communicating with the upper portion of said reservoir and said receptacle, said vent tube providing an overflow from said reservoir through said receptacle and said extension to indicate when 80 said reservoir is filled.

In witness whereof, I have hereunto set my hand this 30th day of March, 1928.

JOHN O. LEWIS.
